(57) **CLAIM**

The ornamental design for a wall cupboard, as shown and described.

DESCRIPTION

FIG. 1 is a front perspective view of a wall cupboard embodied as a first aid cabinet, showing our new design, with the doors open;

FIG. 2 is a view similar to FIG. 1, but with the doors closed; FIG. 3 is a front elevational view of the first aid cabinet with the doors open;

FIG. 4 is a view similar to FIG. 3, but with the doors closed; FIG. 5 is a top plan view of the first aid cabinet with the doors open;

FIG. 6 is a top plan view of the first aid cabinet, but with the doors closed;

FIG. 7 is a bottom plan view of the first aid cabinet with the doors open;

FIG. 8 is a bottom plan view of the first aid cabinet, but with the doors closed;

FIG. 9 is a right side elevational view of the first aid cabinet with the doors open;

FIG. 10 is a right side elevational view of the first aid cabinet, but with the doors closed;

FIG. 11 is a left side elevational view of the first aid cabinet with the doors open; and,

FIG. 12 is a left side elevational view of the first aid cabinet, but with the doors closed.

The material shown in broken line forms no part of the claimed design.
